UNITED STATES PATENT OFFICE.

ELMER CAMBURN, OF TECUMSEH, MICHIGAN.

DEVICE FOR ALINING CUTTER-BARS.

1,161,024.

Specification of Letters Patent. Patented Nov. 23, 1915.

Application filed March 1, 1913. Serial No. 751,527.

To all whom it may concern:

Be it known that I, ELMER CAMBURN, citizen of the United States, residing at Tecumseh, in the county of Lenawee and State of Michigan, have invented certain new and useful Improvements in Devices for Alining Cutter-Bars, of which the following is a specification.

This invention relates to an improvement 10 in cutter-bar adjusting devices and has for its principal object the provision of simple and effective means which may be readily used to aline the cutter-bar of a mowing machine with the pitman-bar.

15 The above and additional objects are accomplished by such means as are illustrated in their preferred embodiment in the accompanying drawings, described in the following specification and then more particularly pointed out in the claim which 20 is appended hereto and forms a part of this application.

With reference to the drawings, wherein, I have illustrated the preferred embodiment 25 of my invention as it is reduced to practice, and throughout the several views of which, similar reference numerals designate corresponding parts; Figure 1 is a top plan view illustrating my alined device in its assembled relation to a cutter-bar. Fig. 30 2 is a side elevation of the adjusting device as separate from the cutter-bar. Fig. 3 is a section on the line 3—3 of Fig. 2. Fig. 4 is a longitudinal section. Fig. 5 is a 35 detail view showing in perspective the rotating drum and bar supporting shaft. Fig. 6 is an end view of the drum.

Proceeding now to the description of the drawings, I have illustrated my invention 40 as applied to a cutter-bar 1 and ground shoe 2 of standard type. The alining device itself includes two main elements the casting designated as an entirety in Fig. 1 by the numeral 3 and the rotating elements 45 designated as an entirety by the numeral 4.

The casting 3 is made of any suitable metal and is formed to produce the base plate 5 carrying at its opposite ends the integrally formed upwardly and vertically 50 projecting bearing boxes 6 and 7. The member 6 is formed with a concave recess in its upper face and is provided with a retaining cap 8 cast with a corresponding recess on its under face and adapted to be 55 held in fixed position on the member 6 by the headed bolts 9 operating in suitably

formed threaded bores. The member 7 is cored laterally to produce a frusto-conical opening for a purpose hereinafter disclosed. A plurality of radially extending internally 60 screw threaded openings are formed in the member 7 and communicate with the frusto-conical opening.

The rotatable element 4 includes a frusto-conical drum 10, from the smaller end of 65 which extends the eccentrically positioned cutter-bar supporting shaft 11, the free end of which terminates in the ball member 12. On the larger end of the drum is formed the nut 13. In assembling the device, the 70 plate 5 is bolted or otherwise secured to the shoe 2. The shaft 11 is then mounted within the sleeve 14 of the coupling arm 15, the drum 10 being disposed within the frusto-conical opening of the member 7. The 75 member 12 is seated in the concave recess of the box 6 and the cap 8 is secured in place by the bolt 9. A set screw 17 is threaded into any one of the openings 18 and by engagement with the drum member 10 holds 80 the shaft 11 and drum 10 in adjusted position. It will be seen that the member 12 in connection with the recesses of the members 6 and 8 form a ball and socket joint.

In regard to the operation of the device, 85 the following brief description is submitted: If the finger bar 1 by constant contact with obstacles of various nature is forced backward out of alinement transverse to the line of advancement of the machine, a wrench or other tool is applied to the member 13 and the shaft 11 is turned in the desired direction. Particular attention is now directed to the fact that the finger bar 1 extends at right angles to the member 90 2 and that the member 2 is connected to the member 15 by the shaft 11. Therefore, since the member 12 of the shaft 11 is mounted for approximate eccentric rotation in the socket wherein it is seated and the 95 other end of the shaft is secured to the drum 10 and is mounted for eccentric rotation therewith, it will be seen that the rotation of the drum 10 will throw the finger bar 1 forwardly or rearwardly of the line of 100 draft of the knives. The shaft 11 being turned to its desired position, it only remains to tighten the set screw 17 to hold the several members in the adjusted position.

In reduction to practice, I have found 110 that the form of my invention, illustrated in the drawings and referred to in the above

description, as the preferred embodiment, is the most efficient and practical; yet realizing that the conditions concurrent with the adoption of my device will necessarily vary, 5 I desire to emphasize the fact that various minor changes in details of construction, proportion and arrangement of parts may be resorted to, when required, without sacrificing any of the advantages of my invention, as defined in the appended claim.

What is claimed is:

In an aliner for cutter bars, the combination with a connecting bar, of a base plate having bearing boxes at each end thereof, 15 one of said boxes having a frusto-conical opening therethrough, a plurality of screw-threaded openings disposed radially with respect to said frusto-conical opening, the

other of said boxes provided with a removable cap, spherical recesses in the boxing 20 and cap coinciding when the cap is applied, means for fastening the cap, the edges of the spherical recess flared, a bar, a frusto-conical drum on one end of the bar, the bar being eccentrically arranged therein, a ball 25 on the other end of the bar coating with the spherical recess in said boxing, turning means on said drum, and means carried by said radial openings for holding the said drum within the frusto-conical opening. 30

In testimony whereof I affix my signature in presence of two witnesses.

ELMER CAMBURN.
